UNITED STATES PATENT OFFICE.

ARTHUR B. CLUNIES, OF ROCHESTER, NEW YORK, ASSIGNOR TO THE SILL
STOVE WORKS, OF SAME PLACE.

DESIGN FOR A FIRE-POT LINING-SECTION.

SPECIFICATION forming part of Design No. 31,196, dated July 11, 1899.

Application filed June 12, 1899. Serial No. 720,299. Term of patent 14 years.

To all whom it may concern:

Be it known that I, ARTHUR B. CLUNIES, a citizen of the United States, residing at the city of Rochester, in the county of Monroe and State of New York, have invented and produced a new and original Design for a Fire-Pot Lining-Section, of which the following is a specification, reference being had to the accompanying drawings, forming a part thereof.

In the drawings, Figure 1 is a perspective view of a fire-pot lining-section, showing my design, looking at the front side; Fig. 2, a similar view looking at the rear corner; Fig. 3, a perspective view showing the bottom and one end, and Fig. 4 an end view.

The characteristic feature of my design is the shape or configuration of the lining-section as a whole.

The front face 1 of the section is curved forwardly near one end and terminates in the rib 2, arranged at an angle relative to the top and bottom lines, and beyond said rib is the substantially flat surface 3. The upper face 4 of the section is substantially flat and extends in the same plane, excepting at one end, where it curves upwardly at 5 to the nar-

rower flat surface 6, the forward edge of the upper face being rounded at 16. The end face 7 of the section extends at a slight angle to the plane of the front surface and has 30 the rounded edge 8 at the upper portion, below which rounded portion is a groove 9, as shown in Fig. 3. The bottom of the section beneath the end 7 is cut away, forming the surface 10, inclined relative to the front and 35 back of the article, and the front edge is also cut away at 11, leaving the projecting surface 12. The end of the bottom face is also slightly inclined at 13. The end 14 of the section is cut away on the rear side at 15, as 40 shown in Fig. 2, and is provided with the recess 17, extending to the bottom, and the rear face 18 is a substantially plane surface, having the outline shown in Fig. 2.

I claim—

45

The design for a fire-pot lining-section substantially as herein shown and described.

ARTHUR B. CLUNIES.
